SAW GUIDE FOR USE IN IMPLANTING
PROSTHESIS IN TOTAL KNEE ORTHO-
PEDIC PROCEDURE

Robert T. Rylee II, 411 N. 3rd at Parkway,
Memphis, Tenn. 38105

Filed Feb. 14, 1973, Ser. No. 332,253

Term of patent 14 years

Int. Cl. D24—02

U.S. Cl. D83—12 R

Fig. 1

FIG. 1 of the drawings is a perspective view of the saw guide; and

FIG. 2 is a perspective view as seen from the rear of FIG. 1.

I claim:

The ornamental design of a saw guide for use in implanting prosthesis in total knee orthopedic procedure, as shown and described.
